UNITED STATES PATENT OFFICE.

JAMES S. REID, OF HARRISBURG, ILLINOIS.

RAILROAD SWITCH.

1,406,079.

Specification of Letters Patent. Patented Feb. 7, 1922.

Application filed August 25, 1921. Serial No. 495,260.

To all whom it may concern:

Be it known that I, JAMES S. REID, a citizen of the United States, residing at Harrisburg, in the county of Saline and State of Illinois, have invented certain new and useful Improvements in Railroad Switches; and I do declare the following to be a full, clear, and exact description of the invention, such as will enable others skilled in the art 10 to which it appertains to make and use the same.

This invention relates to an improved railroad switch and one object of the invention is to provide a switch so constructed 15 that the switch can be set to permit a train to enter a side track and while so set permit a train moving along the main track from the opposite direction to pass over the switch and continue along the main track without 20 danger of being derailed.

Another object of the invention is to provide a switch having the switch point mounted in a novel manner and so mounted that it may have easy swinging movement 25 but at the same time be prevented from having vertical movement.

Another object of the invention is to provide a switch so constructed that the main body portion thereof including rail sections 30 for connection with the rails of the main track and side track may be cast in one piece and easily put in place.

Another object of the invention is to provide a switch having improved means for 35 guiding the wheels over the switch point.

This invention is illustrated in the accompanying drawings, wherein:

Figure 1 is a top plan view of the improved switch.

40 Figure 2 is a view showing the improved switch in side elevation.

Figure 3 is a bottom plan view of the switch.

Figure 4 is a transverse sectional view 45 through the switch taken along the line 4-4 of Fig. 1.

Figure 5 is a top plan view of one of the side castings forming part of the switch.

Figure 6 is a perspective view of a switch 50 point which will be mounted upon the casting shown in Fig. 5.

This switch is used in connection with a railroad track and will be mounted upon the ties 1 between the rails 2 and 3 of the 55 main track and will serve the usual purpose of guiding a train either from the rails 2

of the main track to the rails 3 thereof or from the rails 2 of the main track to the rails 4 of a side track. As previously stated, the object of the invention is to provide a 60 switch so constructed that with the switch set to guide a train from the rails 2 to the rails 3 or to the rails 4, a train approaching from the opposite direction along the rails 3 or 4 may pass over the switch without 65 danger of being derailed.

This improved switch is provided with side sections of a duplicate construction and therefore only one side will be described in detail. Each of the side portions is provided with a body portion including a base plate 5 which will be spiked to the ties by means of spikes 6 which pass through spike-receiving openings 7 formed in the base plate. Rail sections 8 and 9 for co-operation 70 with the rails 2 and 3 of the main track are cast upon the plate 5 and a rail section 10 for co-operation with the rails 4 of the side track is also cast upon the base plate adjacent the rail sections 9. An upstanding 75 flange or strip 11 extends longitudinally of the plate 5 and extends above a runner 12 which is positioned between the strip 11 and rail section 10 as shown in Fig. 5 so that the flange of a wheel when leaving the rail section 10 may rest upon this runner strip 12. This runner strip 12 has one end portion 80 tapered as shown at 13 and has this tapering end portion 13 terminating short of the end of the flange 11 and beveled from its upper 85 face to provide a sloping end portion 14 as shown in Fig. 5. This sloping end portion 14 terminates short of the end of the rail section 8 but the strip 11 is extended as 90 shown into relatively overlapping relation 95 to this rail section 8. The inner end of the rail section 8 is rounded as shown in Fig. 5 and has its lower portion undercut to provide a pocket 15 as shown in Fig. 2 and the ends of the rail sections 9 and 10 and block 100 16 which braces their converging ends are undercut to provide a pocket 17 so that the switch point may have swinging movement but will be prevented from having vertical 105 movement.

The switch point 18 fits upon the base between the rail sections and has one end portion cut out to provide a seat 19 and tongue 20, the seat 19 being provided to receive the rounded end of 110 the rail section 8 when the tongue 20 which forms part of the switch point 18 is fitted

into the pocket 15 of the rail section 8. The end of the tongue 20 is curved to conform to the curvature of the upstanding wall at the inner end of the seat 19 so that 5 the rail at the inner end of the pocket 15 which is curved similar to the rounded end of this rail section above the pocket will be properly engaged and the switch point permitted to swing easily in the arc of a 10 circle. At the opposite end, the switch point is cut away from its upper face thus providing a tongue extension 21 for extending into the pocket or cutout 17. These 15 tongues 20 and 21 do not interfere with free swinging movement of the switch point but at the same time they prevent the switch point from having vertical movement. Therefore, the tread portion of the switch point will be held in proper position relative to the treads of the rail sections 8, 9 and 10. This switch point is provided at one end with a depression or groove 22 which decreases in depth as shown in Fig. 6 until it merges into the upper face of 20 the switch point and at its opposite end has its inner side portion cut away to provide a face 23 which slopes downwardly toward the end of the switch point and gradually decreases in width. From an inspection of 25 Fig. 6 and Fig. 1, it will be seen that this cutting of the switch point provides a section 24 which will form a continuation of the rail section 8 and sections 25 and 26 which will form continuations of the rail 30 sections 9 and 10.

The base plates 5 are provided with tongue extensions 27 which extend inwardly and form supports for a housing 28 which housing is provided with a raised central 40 portion 29 in which is slidably mounted a draw-bar 30. This draw-bar 30 is connected with the switch point by fasteners which pass through the draw-bar and through side ears 31 of the switch points and it will 45 thus be seen that when the draw-bar is moved by means of a suitable mechanism not shown, the switch points will be moved together to set the switch and direct a train either along the main track or into a side track. Arcuate slots 32 are provided in the 50 base plate and receive pins 33 carried by the switch points so that the swinging of the switch points will be guided and the amount of swing permitted limited. After 55 the switch has been set in a desired position, a securing pin 34 which is carried by a chain 35 is passed through an opening in the connecting bar or housing and through an opening formed in the draw-bar. 60 This draw-bar is provided with two of the pin receiving openings so that the switch points can be secured against movement after being properly set to direct the train along the main track or into a side track.

65 With the switch set as shown in Fig.

1, a train moving along the track from the left-hand side of the figure will be directed from the rails 2 across the switch and over the rail sections 10 onto the rails 4 of the side track. With the switch still set in this 70 position, a train moving along the main track and approaching the switch from the right-hand side of this figure will pass from the the rails 3 onto the rail sections 9. Upon reaching the switch, the flange of the wheels 75 upon one side will pass between the sections 25 and 26 of the switch and the wheels after leaving the groove 22 will pass across the upper face of the switch point and when the flanges of the wheels reach the sloping portion 23 of the switch point, the wheels will engage the end portion 24 of the switch point and after passing over this portion, roll along the rail section 8 onto the rails 2. During this operation, the wheels at the 80 opposite side of the train will pass out of engagement with the rail section 9 and the flanges of the wheels will rest upon and roll along the strip 12. The guiding flange 11 by engaging the flanges of the wheels 90 will prevent the wheels from leaving the strip 12. This strip 12 is of the proper thickness so that when the wheels reach the end of the strip 12, the flanges of the wheels will engage the end portion 24 of 95 the switch point and will ride onto the rail section 8 at the same time that the wheels of the first mentioned side of the train engage the rail section 8. It will thus be seen that with this construction, a train 100 may enter a siding and a second train approaching the switch from the opposite direction may pass over the switch without it being necessary to reset the switch and without any danger of the second train being derailed. With the switch set in the opposite direction, the first train would move along the main track and over the switch onto the rails 3 of the main track and a train moving out of the side track could pass over 105 the switch and continue along the main track without danger of being derailed and without it being necessary to reset the switch. A switch has thus been provided which will be very effective in operation 110 due to the fact that the wheels can be properly guided and also due to the fact that the switch points may have the proper transverse swinging movement and be held against vertical movement.

I claim:

1. A main track, a side track, and a switch structure for controlling passage of trains along the main and side tracks, said switch structure comprising side sections each having a base plate, rail sections rigid with the end portions of the base plate and extending in alignment with the rails of the main and side tracks, a switch point extending longitudinally of the base plate be- 115 120 125 130

tween the rail sections carried by the end portions thereof, tongues extending from the ends of the switch point and fitting into pockets in the rail sections of the base to hold the switch point against vertical movement, and means for simultaneously imparting transverse swinging movement to the switch points of the side sections and releasably holding the switch points in a set position.

2. A main track, a side track, and a switch structure for controlling passage of trains along the main and side tracks, said switch structure comprising side sections each having a base plate, rail sections rigid with the end portions of the base plate and extending in alinement with the rails of the main and side tracks, a switch point extending longitudinally of the base plate between the rail sections carried by the end portions thereof, a wheel engaging and guiding strip extending longitudinally of the base plate to one side of the switch point, and extending in relatively overlapping relation to the rail sections at the ends of said base plate, a wheel supporting strip between the switch point and guiding strip, and means for moving the switch points transversely and releasably holding the same in a set position.

3. The structure of claim 2 having the wheel supporting strip terminating short of the rail section at one end of the base plate and tapered transversely whereby the said tapered end portion of the wheel supporting strip will be out of engagement with

the switch point when the switch point is swung into engagement with the supporting strip.

4. A main track, a side track, and a switch structure for controlling passage of trains along the main and side tracks, said switch structure comprising side sections each having a base plate, rail sections rigid with the end portions of the base plate and extending in alinement with the rails of the main and side tracks, a switch point extending longitudinally of the base plate between the rail sections carried by the end portions thereof, means for holding the switch points against vertical movement and means for swinging the switch points transversely to an adjusted position.

5. The structure of claim 4 having the switch point provided with a longitudinally extending groove increasing in depth toward the end of the switch point and adapted to receive the flange of a wheel moving off of a rail section at the end of the base plate, the opposite end portion of the switch point being tapered and having one side portion sloping downwardly toward the end of the switch point and forming the second side portion of the last mentioned end portion of the switch point, a rail section forming a continuation of the rail section upon the end of the base plate.

In testimony whereof I have hereunto set my hand.

JAMES S. REID.
